UNITED STATES PATENT OFFICE

120,609

DESIGN FOR A COMBINATION FIREMAN'S AX AND WRECKING TOOL

Ervin B. Arnsbarger, Lakewood, Ohio

Application February 17, 1940, Serial No. 90,341

Term of patent 14 years

To all whom it may concern:

Be it known that I, Ervin B. Arnsbarger, a citizen of the United States, residing at Lakewood, in the county of Cuyahoga and State of Ohio, have invented a new, original, and ornamental Design for a Combination Fireman's Ax and Wrecking Tool, of which the following is a specification, reference being had to the accompanying drawing, forming part thereof.

In the drawing:

Fig. 1 is a perspective view of a combination

fireman's ax and wrecking tool embodying my new design;

Fig. 2 is a top plan view thereof; and

Fig. 3 is an end elevational view of the tool shown in Fig. 1.

I claim:

The ornamental design for a combination fireman's ax and wrecking tool, substantially as shown.

ERVIN B. ARNSBARGER.
